UNITED STATES PATENT OFFICE.

JOHN GEMZA, OF BROWNVILLE, MAINE, AND CONSTANTY BALAZY, OF DONORA, PENNSYLVANIA.

COMBINATION LOCK.

Application filed September 15, 1924. Serial No. 737,653.

To all whom it may concern:

Be it known that JOHN GEMZA and CONSTANTY BALAZY, both citizens of Poland, residing at Brownville and Donora, respectively, in the counties of Piscataquis and Washington and States of Maine and Pennsylvania, respectively, have invented certain new and useful Improvements in Combination Locks, of which the following is a specification.

This invention relates generally to combination locks, being here shown as embodied in a padlock comprising a body member and a movable shackle.

The invention has for an object the provision of a novel type of combination lock whose distinguishing feature is the lack of any fixed or set combination, and which may be set to any desired combination each time the lock is applied.

For further comprehension of the invention, and of the objects and advantages thereof, reference will be had to the following description and accompanying drawing, and to the appended claims in which the various novel features of the invention are more particularly set forth.

Fig. 1 of the drawing is a face view of my improved lock.

Fig. 2 is a side view thereof.

Fig. 3 is a transverse sectional view taken on the line 3—3 of Fig. 2.

Fig. 4 is an end view of the lock.

Fig. 5 is a longitudinal sectional view taken on the line 5—5 of Fig. 1.

Fig. 6 is a longitudinal sectional view at right angles to Fig. 5 and taken on the line 6—6 of the latter figure.

Fig. 7 is a fragmentary transverse sectional view taken on the line 7—7 of Fig. 5.

Fig. 8 is a fragmentary longitudinal sectional view taken on the line 8—8 of Fig. 7.

As here embodied our improved lock comprises an elongated rectangular casing 10. Slidably mounted on opposite sides of this casing are the flat bars 11 which are united at one end by a cross-bar 12 to which a hooked bolt or shackle 13 is rigidly fixed. This shackle is guarded by a hood 15 that is fixed to the end of the casing and is formed with a pair of apertures 16 that accommodate the shank and hook of the shackle respectively. The bars 11 are formed with longitudinal slots 18 in which engage the guide pins 19 fixed in the side walls of the

casing 10, an additional guide pin 20 being fixed to the end of the casing and passing through a suitable aperture in the crossbar 12. For convenience I will designate this end of the casing as the front end. The bar 12 is yieldingly held in position bearing on the front end of the casing, and with the hook of the shackle engaged in the aperture in the hood 15, by means of the tension springs 22 that are connected at one end to the casing and at their other ends to the ends of the side bars 11.

Fixed to the lower edges of the side bars 11, and projecting downward therefrom are the rows of pins 25 which are engaged in a manner to be presently pointed out to retain the shackle 13 in the above mentioned locking position. Each side wall of the casing is formed at its bottom portion with a series of vertical slots 26 corresponding in longitudinal spacing to the pins 25, into which project the ends of yoke-like cross-pieces 27 that carry studs or pins 28 on their ends which engage between the pins 25 to hold the shackle in locked position. As clearly shown in Fig. 3 of the drawing these crosspieces 27 are of such length that by a slight movement thereof laterally of the casing the studs 28 may be projected between the pins on either side of the casing, the ends of the studs lying within the confines of the rows of pins 25 when the members 27 are in intermediate or neutral positions. These members 27 are supported by the springs 29 attached to a longitudinal bar 30 on the bottom of the casing and bearing at their ends on the individual members 27.

To impart transverse movement to selected ones of the members 27 we provide the following means: A shaft 33 that is of square cross section throughout its main length extends longitudinally through the casing just above these members, this shaft being suitably journaled at its ends in the casing walls. Slidably mounted on this shaft are three arms 34 that have square apertures therein through which the shaft passes. The hub portions of these arms are straddled by the forked lower ends of uprights 35 that are formed with circular apertures 36 through which the shaft 33 passes freely. The upper ends of these uprights are located close to the top of the casing, the uprights being formed at a distance below their upper ends with apertures through which passes a lon-

gitudinal guide rod 37 fixed at its ends in the casing walls. The top wall of the casing 10 is formed with a longitudinal slot 38 through which project the upper ends of the 5 levers 39 fulcrumed between their ends to the uprights 35, these levers having laterally turned pointer elements 40 on their upper ends that are adapted to register with certain numbered marks 41 on the top of the 10 casing, these marks having a spacing along the casing corresponding to that of the members 27. At a short distance below its upper ends each upright 35 has set slidably therein a pair of oppositely projecting transverse pins 42 that are urged outwardly by a 15 spring 43 bearing on their inner ends. The outer ends of these pins are pointed and are adapted to bear yieldingly on the adjacent faces of strips 44 slidably supported in the 20 guide elements 45 for transverse movement in the casing, these strips being urged transversely inward in the casing by means of the springs 46. The inner faces of these strips are formed with shallow vertical 25 notches 47 in which the ends of the pins 42 are adapted to engage when the pointers 40 are in registry with the different marks 41 on the top wall of the casing.

It will be apparent that by moving these 30 uprights 35 longitudinally in the casing the arms 34 on the shaft 33 may be brought into registry with selected ones of the members 27 so that rotary movement of the said shaft will cause the arms to engage the selected 35 members and move the same into or out of neutral position. As here shown the members 27 are provided on their top sides with cam projections 27' that are engaged by the ends of the arms 33. To rotate the shaft 40 34 the latter has a bevel pinion 50 fixed on one end that is engaged by a bevel gear 51 on the lower end of a vertical shaft 52 mounted in the rear end of the casing 10, the upper end of this shaft 52 projecting 45 from the casing and having a knob 53 thereon for purposes of rotation.

To move the uprights 35 along the casing we provide the following means. A pair of vertical shafts 55 and 56 respectively 50 are mounted in the front and rear ends of the casing, the shaft 55 projecting at its upper end from the casing and having thereon a knob 57. These shafts have pulleys or drums 58 fixed thereon, around which 55 a belt 59 is looped, this belt being of circular cross section, and passing through suitable apertures in the uprights 35. Fixed on this belt is a spherical member 62 that is adapted to engage suitable displaceable 60 devices mounted on the uprights 35 to move the latter along the casing 10. These displaceable devices are here formed by the lower ends of the levers 39, the levers being accommodated in vertical grooves 63 in the 65 uprights 35. At their lower ends these

levers are forked and straddle the belt 59, the forks presenting an opening or notch of less diameter than the member 62, so that when said member engages one of the forks it causes the upright, to move along with the belt 59. The grooves 63 in the uprights are deepened above the fulcrum points 39' of the levers 39 while the lower ends of the levers are pressed against the uprights by spring such as 64. 70

To retain the members in locking position we provide a pair of longitudinal bars 70 that are slidably mounted one on each side of the casing and have flat levers or fingers 71 projecting upward therefrom. 80 These fingers 71 are moved into and out of engagement in transverse slots 72 in the members 27 by longitudinal movement of the bars 70. The longitudinal movement of the bars 70 is effected by the bell crank levers 73 fulcrumed at the sides of the casing and engaging the bars 70 at one end and being connected at opposite ends to the lower ends of links 74 that are connected at their upper ends to vertically shiftable 85 straps 75.

The manner of operation of our improved device is as follows:—Assuming the shackle to be in locking position but with the combination not set and the members 27 also in neutral position. Knob 57 is rotated to cause the part 62 on the belt 59 to engage the ends of the levers 39 to move the uprights to selected position with the pointers 40 registering with certain of the marks 41. 90 The knob 53 is then rotated, causing the shaft 34 to rock and the arms 43, which have been positioned in registry with certain of the members 27 to engage these members and move them to locking position. The knob 57 is then rotated to move the uprights 35 back to the rear end of the casing. 95 As will be apparent, in order to release the shackle it will be necessary to again set the uprights 35 to the position previously occupied in order to bring the arms 34 into 100 operative relation to the three members 27 that have been moved to locking position. To move the shackle 13 to releasing position we may provide a cam 75' mounted in the lower end of a shaft 76 and adapted to bear on the crosspiece 12 when the shaft 105 is rotated. The shaft 76 has a knob 77 on its upper end for rotation. 110

Having thus described our invention what we claim as new and desire to protect by Letters Patent of the United States is as follows:—

1. In a combination lock, a rectangular casing, a movable locking element having fixed thereto a pair of bars extending along the opposite sides of the casing, projections spaced along said bars, a series of transversely movable plunger members adapted to be selectively moved to engage at their ends 125

between said projections to lock the said element, and devices adapted to selectively engage said plunger members to move certain ones thereof to operative position.

5 2. In a combination lock, a rectangular casing, a movable locking element having fixed thereto a pair of bars extending along the opposite sides of the casing, projections spaced along said bars, a series of trans-
10 versely movable plunger members adapted to be selectively moved to engage at their ends between said projections to lock the said element, and devices adapted to selectively engage said plunger members to move
15 certain ones thereof to operative position, said devices comprising a series of arms and a shaft on which said arms are slidably mounted.

3. In a combination lock, a rectangular casing, a movable locking element having fixed thereto a pair of bars extending along the opposite sides of the casing, projections spaced along said bars, a series of trans-
20 versely movable plunger members adapted to be selectively moved to engage at their ends between said projections to lock the said element, and devices adapted to selectively engage said plunger members to move certain ones thereof to operative position, said
25 devices comprising a series of arms and a shaft on which said arms are slidably mounted, and means for moving said arms along said shaft.

30 4. In a combination lock, a rectangular casing, a movable locking element having fixed thereto a pair of bars extending along the opposite sides of the casing, projections spaced along said bars, a series of trans-
35

versely movable plunger members adapted to be selectively moved to engage at their ends between said projections to lock the said element, and devices adapted to selectively engage said plunger members to move certain ones thereof to operative position, said devices comprising a series of arms and a shaft on which said arms are slidably mounted, and means for moving said arms along said shaft, comprising uprights straddling said arms, guiding means for said uprights, and a belt displaceably engaged with said uprights.

5. In a combination lock, a rectangular casing, a movable locking element having fixed thereto a pair of bars extending along the opposite sides of the casing, projections spaced along said bars, a series of trans-
40 versely movable plunger members adapted to be selectively moved to engage at their ends between said projections to lock the said element, and devices adapted to selectively engage said plunger members to move certain ones thereof to operative position, said devices comprising a series of arms and a shaft on which said arms are slidably mounted, and means for moving said arms along said shaft, comprising uprights straddling said arms, guiding means for said uprights, and a belt displaceably engaged with said uprights.
